UNITED STATES PATENT OFFICE.

ALDEN W. DERBY, OF LEOMINSTER, MASSACHUSETTS.

STEP-LADDER.

No. 850,142.

Specification of Letters Patent.

Patented April 16, 1907.

Application filed March 8, 1906. Serial No. 304,879.

To all whom it may concern:

Be it known that I, ALDEN W. DERBY, a citizen of the United States, residing at Leominster, in the county of Worcester and State of Massachusetts, have invented certain new and useful Improvements in Ladders, of which the following is a full, clear, and exact description of the same.

This invention relates to ladders; and it is designed primarily for use in gathering fruit from trees, in which connection it can be utilized without liability of injury to the tender branches of the tree, although it is obviously useful as a step-ladder for household purposes.

It is an object of this invention to produce a ladder with a relatively wide base or space between the sides thereof and at the same time prevent sagging of the rungs of the ladder through the agency of a novel brace.

It is also an object of this invention to provide a standard with novel means for anchoring the ladder in order that displacement thereof when in use will be wholly obviated.

Furthermore, an object of the invention is to provide novel means for retaining the ladder-sections in assembled folded relation when stored or out of use.

Means are also provided for retaining the sections of the ladder in proper relation when the same is in use.

With the foregoing and other objects in view the invention consists in the details of construction and in the arrangement and combination of parts, to be hereinafter more fully set forth and claimed, whereby a ladder is produced which will possess advantages in points of utility, efficiency, and durability and prove comparatively inexpensive to manufacture.

In describing the invention in detail reference will be had to the accompanying drawings, forming part of this specification, wherein like characters denote corresponding parts in the several views, in which—

Figure 1 is a view in elevation, illustrating the front of the ladder. Fig. 2 illustrates a side elevation thereof with the parts in operative position. Fig. 3 is an enlarged detail of fragments of the ladder, showing the securing means.

In the drawings, 1 1 denote the two sides of the ladder, converging toward the top and having slightly bent portions 2 2 to cause the said sides to lie approximately parallel at the upper end of the ladder.

A suitable standard 3 has its upper end between the parallel sides, connected by a bolt 4, having a thumb-nut 5, whereby the parts may be fastened against movement when the proper adjustment is attained.

As a further means for retaining the standard in suitable operative relation to the sides of the ladder I may provide the said standard with a hook 6, designed to engage the links 65 of a chain 7, extending from one of the rungs of the ladder.

The rungs 8 have their ends suitably anchored in the sides of the ladder and gradually diminish in length toward the top; but as the distance between the sides of the ladder toward the bottom is so great as to allow certain sagging of the rungs I attach a brace 9 to each rung where the distance between the sides warrants it. I prefer to provide the standard with a spur or point 10, which will embed itself in the ground and aid in holding the ladder against movement. The sides might also be provided with like anchoring devices when the ladder is to be used outside the house; but when used as a step-ladder it is the purpose of the inventor to provide pads or feet of rubber to be attached to the ends of the standard and sides, doing away with the spurs, of course, when the ladder is in use for household purposes.

The brace 9 extends slightly above one of the rungs midway the length of the ladder, and in order to hold the standard 3 in a folded position with relation to the sides I provide a link 11, pivoted to the standard and adapted to swing over the upper end of the brace.

From an inspection of the drawings it will be apparent that sidewise displacement of the ladder will be prevented, owing to the width of the base, and as the standard is secured with relation to the sides of the ladder a very strong unyielding structure is afforded when properly adjusted and secured.

Having fully described the invention, what I claim as new, and desire to secure by Letters Patent, is—

1. In a ladder, suitable sides, a standard pivotally connected thereto, rungs connecting the sides, a brace attached to the rungs, and a link pivoted to the standard adapted to engage the end of the brace.

2. In a ladder, suitable sides, a standard therebetween, a bolt for pivotally connecting the standard and sides, means for clamping the sides and standard to hold them friction-

ally against displacement, rungs for the ladder, a brace connecting certain rungs.

3. In a ladder, a suitable ladder-section, a brace connecting rungs of said ladder-section, and extending slightly beyond the last of said rungs to which it is attached, a standard pivoted to the ladder, and a link pivoted to

the standard and adapted to swing over the end of the brace.

ALDEN W. DERBY.
